(57) **CLAIM**

The ornamental design for a control module for a dental light hardening device, as shown and described.

DESCRIPTION

1. Control module for a dental light hardening device.

Fig. 1.1 is a left side view of a control module for a dental light hardening device, showing my new design.

Fig. 1.2 is a right side view of the control module for a dental light hardening device in Fig. 1.

Fig. 1.3 is a right side view of the control module for a dental light hardening device in Fig. 1 without the battery and light guide.

Fig. 1.4 is a left side view of the control module for a dental light hardening device in Fig. 1 without the battery and light guide.

Fig. 1.5 is a top view of the control module for a dental light hardening device in a partial view of Fig. 1.

Fig. 1.6 is a first alternate top view of the control module for a dental light hardening device in a partial view of Fig. 1.

Fig. 1.7 is a second alternate top view of the control module for a dental light hardening device in a partial view of Fig. 1.

Fig. 1.8 is a third alternate top view of the control module for a dental light hardening device in a partial view of Fig. 1.

Fig. 1.9 is a fourth alternate top view of the control module for a dental light hardening device in a partial view of Fig. 1.

The broken lines shown are included for the purpose of illustrating portions of the control module for a dental light hardening device that form no part of the claim.

1 Claim, 7 Drawing Sheets
